UNITED STATES PATENT OFFICE.

BRUNO KIPPELS, OF MOORHEAD, MINNESOTA.

MERRY-GO-ROUND.

No. 797,439.

Specification of Letters Patent.

Patented Aug. 15, 1905.

Application filed May 27, 1904. Serial No. 210,051.

To all whom it may concern:

Be it known that I, BRUNO KIPPELS, a citizen of the United States, residing at Moorhead, in the county of Clay and State of Minnesota, have made certain new and useful Improvements in Merry-Go-Rounds, of which the following is a specification.

My invention is an improvement in what are variously termed "merry-go-rounds," "carousels," and "roundabouts." It is more particularly an improvement upon the machine or apparatus for which I have obtained Letters Patent No. 698,294.

My invention embodies several improvements, as hereinafter specified, and illustrated in the accompanying drawings, in which—

Figure 1 is a perspective view of the apparatus or machine as in use. Fig. 2 is a side view of a portion of the propelling mechanism. Fig. 2^a is a side view of a ratchet forming part of the propelling mechanism. Fig. 3 is a vertical central section illustrating the upper and lower bearings on the central fixed post. Fig. 4 is a sectional view of one of the pedal attachments. Fig. 5 is a section illustrating a bearing for the pedal bar or rod.

A foundation-post 1 is set vertical in the ground, and upon it is supported an iron post 2, the same extending to the requisite height to afford a support for the revolving portion of the apparatus. A collar 3 (see Figs. 1 and 2) is secured to the upper portion of the post 2, and a socket-wheel 4 is arranged above the same and supported by ball-bearings 5, so as to run with minimum friction. In the sockets of part 4 is supported a series of radial arms 6, from whose outer ends seats 7 7^a are suspended by means of bifurcated rods 8, as in my former invention. The seats 7^a are adapted to support a number of persons; but the seat 7 is adapted for one person only—that is to say, the operator who propels the entire revoluble part. As indicated in Fig. 1, the wheel 4 is provided with pendent flanges, between which the bars 6 are arranged, the latter being secured by bolts 9. Above said wheel 4 is arranged a bevel-gear 10, the same being secured or fixed to the post 2. The propelling mechanism is engaged with this gear 10, as will now be described. A shaft 11 (see Fig. 1) is arranged directly above one of the radial bars 6 and supported in bearings 12 and 13, which are in the nature of brackets, the same being provided with base-flanges and securely bolted to the bars 6. The inner end of the shaft 11 is provided with a

bevel-pinion 14, which engages the gear 10. It is apparent that if the shaft 11 be rotated the entire motor part of the apparatus will be carried around the post 2. In my former invention I employed for this purpose a gear-ring and pedal-bars which were so constructed and connected that the pedal-bars were constantly reciprocated. In the present invention I have adopted such a construction and combination of parts that the pedal-bars are at rest save when the operator is actively propelling the apparatus. The details are as follows: The brackets 13, before referred to, are extended horizontally, and in their outer ends a double crank-shaft 15 is provided with bearings. To the opposite cranks of this shaft the pedal-bars 16 are pivotally attached. Upon the central portion of the crank-shaft 15 is keyed a driving spur-gear 17, which meshes with a driven gear 18, mounted loose on the shaft 11. Adjacent to such gear 18 is arranged a sleeve 19, (see Figs. 1, 2, 2^a), having inclined teeth formed on its inner end and secured to the shaft 11 by a clamp-bolt 20. Pawls 21 (see Figs. 1 and 2) are pivoted to the loose gear 18 and provided with springs which serve to hold them normally engaged with the teeth of sleeve 19. The pedal bars or rods 16 are provided with pedals proper, 16^a. These are adapted for vertical adjustment, the same being secured to the rods 16 by means of clamp-bolts 16^b, arranged in slots, as shown in Figs. 1 and 4. By applying pressure alternately to the opposite pedals 16^a the rods 16 will be reciprocated and the crank-shaft 15 rotated. The direction of rotation is indicated by the arrow in Fig. 1, and the loose gear 18 on the drive-shaft 11 will obviously be driven in an opposite direction or forward, whereby its pawls 21 engage the toothed sleeve 19, and the shaft 11 will be driven in the same direction as the gear 18, and thus the entire revoluble part of the apparatus, consisting mainly of rotatable bars 6 and the suspended seats 7 and 7^a, will be driven around the central post 2. When a sufficient speed has been attained and the operator desires for this or any other reason to cease propulsive effort, it is apparent that the bars 16 may hang motionless from the crank-shaft 15, since the gear 18 will run backward on the shaft 11, its pawls in such case riding over sleeve 19. By this simple construction and combination of parts I am enabled to connect the primary driving or crank shaft 15 with shaft 11 in such a manner

that when a due speed has been attained it will not be reduced by the gravity of the outer or pedal bars when the operator ceases propulsive effort. I thus avoid a serious objection to the merry-go-rounds of this class, and especially to that covered by my aforesaid patent.

The seat 7 is supported upon parallel bars 22, and these in turn are connected with parallel bars 23, the two sets of bars 22 23 being arranged at right angles to each other and duly spaced apart. Each of the bars is provided with a lengthwise slot, and clamp-bolts 24 are inserted through coincident slots for securing the two sets of bars together in any required adjustment. The front ends of the bars 23 are provided with slots adapted to receive the pedal-rods 16 and also to provide space for antifriction-rollers 25, (see Fig. 5,) so that the rods 16 work vertically with minimum friction. It will be seen that the slots in the bars 22 23 permit the bars 23 to be adjusted nearer each other or farther apart and also to be adjusted forward. By said adjustments the said bars 23 may be placed a distance apart and projected forward, according to the size and convenience of the operator. The entire seat-support 7 22 23 is loosely connected with the revolving rigid portion of the frame by means of a link or rod 26, (see Fig. 1,) so that the operator is not swung outward by centrifugal action, as is the case with the occupants of seats 7^a.

The radial bars 6, from which the seats are suspended, are supported by diagonal braces 6^a, and the lower ends of the latter are slotted

and secured to lugs 27, (see Fig. 3,) forming an integral portion of a revolving base 28. The latter is constructed as a bevel-gear and rests upon ball-bearings 29, so it may rotate easily around the post 2. It is constructed as a gear to provide for attachment of a driving-gear for the purpose of propelling the apparatus by motor of any suitable kind should this at any time be desirable or practicable. The bars 6 and braces 6^a are connected by vertical bars 6^b, the same being arranged close to the post 2 and duly secured by screw-bolts to the bars 6 6^a.

By the above-described construction, arrangement, and combination of parts I form a merry-go-round which is distinguished by maximum strength, lightness, and ease of propulsion. It may be produced at small cost and easily set up or removed.

What I claim is—

The combination, with a central post and a gear fixed thereon, a series of radial arms attached to a member adapted to revolve around said post, of a series of seats suspended from said arms, one of them formed of cross-bars arranged at right angles to each other and provided with lengthwise slots, clamping-bolts passing through said slots, vertically-reciprocating pedal-bars forming a part of the propelling mechanism and arranged in suitable guides in two of the aforesaid cross-bars, substantially as described.

BRUNO KIPPELS.
